MARKING MACHINE

Newell V. Dyer, Brockton, Mass., assignor to
 United Shoe Machinery Corporation, Paterson,
 N. J., a corporation of New Jersey

Application July 6, 1936, Serial No. 89,165

22 Claims. (Cl. 101—21)

This invention relates to marking machines and is illustrated herein as embodied in a machine of the type disclosed in Letters Patent of the United States No. 1,172,897, granted February 5 22, 1916, in the name of F. W. Merrick.

For the purpose of identifying articles such as shoe parts, for example, during or after their manufacture, it is often desirable to mark them with several rows of characters. Owing to the 10 great variety of styles and sizes of shoes which are usually identified by the characters in one row of the mark, such characters must be readily changeable for convenience in manufacture. To this end, marking machines have commonly been 15 provided with type members mounted or formed upon endless carriers adapted to be moved to bring a selected type member into operative position; but such a construction gives rise to the difficulty of obtaining perfect alinement of the 20 selected type members of the different carriers, which is desirable for the sake of the appearance of the mark and which is necessary to avoid interference between the selected type members in question and other auxiliary members closely adjacent thereto which are employed to make other 25 useful characters in the mark.

In view of the foregoing, an object of the invention is to make provision for facilitating the resetting of type members of machines of the 30 sort referred to above and to insure greater accuracy in locating in operative position the type member or members selected to make a mark.

This object is attained, in the illustrated machine, by the use of articulated rigid type members arranged in the form of a chain looped about spaced supports, one of the supports having positioning edges or surfaces adapted to be enveloped by different type members, including the selected type member, whereby the selected 35 member is located and positively held in its operative position as a result of moving the chain into engagement with the positioning edges or surfaces.

Although the invention may have application 40 to marking machines employing, with or without heat, a suitable marking medium such as ink or a composition including metallic powders, it is disclosed herein with reference to a machine adapted to make a branded mark by the use of 45 heated type members only, the selected type members being heated by the support which is arranged to support them against marking pressure. Since some type members remain in their operative positions for a considerable length of 50 time while others are reset more frequently in

order to change the mark, it is apparent that uniformity in the different characters of the mark depends to a great extent upon the rapid heating of the frequently changed type members and uniformity in the temperature of all the type 5 members selected to make a mark. Moreover, in shoe manufacture, a group of shoe parts of different sizes are usually stacked or placed in order so that changes in their marking require merely the step-by-step movement of one chain of 10 type members arranged progressively in accordance with the order of their characters. In order to obviate delay in bringing a newly selected type member to the proper temperature, the heated support for the selected type members is arranged, as another feature of the invention, to be engaged also by the succeeding type member so that the latter will have been heated to the 15 desired temperature by the time that it is moved into the operative position. Since a type plate is 20 usually provided, in order to get several rows of characters, separate heating units are provided for the movable type plate thereby making it easy to heat these characters to the same 25 temperature as those on the type chains.

The invention also contemplates the provision in the type members of heat conductors having relatively high heat conductivity and adapted to transmit heat rapidly from the heating means to 30 the type faces of the members.

With the above and other objects in view, the invention will now be described with reference to the accompanying drawings and will be pointed out in the appended claims.

In the drawings,

Fig. 1 is a view in perspective of an illustrative machine embodying the present invention;

Fig. 2 is a view in front elevation of the marking head of the machine illustrated in Fig. 1;

Fig. 3 is a sectional elevation of the marking 40 head, the section being taken along the line III—III in Fig. 2;

Fig. 4 is a view in side elevation of the marking head, certain parts being broken away;

Fig. 5 is a perspective view illustrating the 45 locating of a type member in operative position;

Fig. 6 is a view similar to Fig. 5 illustrating in perspective an alternative form of type member;

Fig. 7 is a sectional view of a part of the re- 50 setting mechanism; and

Fig. 8 is a perspective view of the work piece having a mark of the type which the illustrated machine is adapted to make.

The illustrated machine comprises a marking 55

head 10 (Fig. 1) mounted for movement with a parallel motion toward and from a work support 12 to mark a work-piece on the support in the manner illustrated in Fig. 8. The marking head 10 comprises a carrier 14 supported for movement in parallel vertical positions by a walking beam 16 and a link 18 which are pivotally mounted between side members 20 of the machine frame 21. The beam 16 is oscillated by 10 a link 22 which is driven from a crank shaft 24 by connections of the type disclosed in the Merrick patent mentioned above to which reference may be made for a more detailed description of the mechanism of the illustrated machine 15 just described.

Since it is often desirable to be able to identify a work-piece, such as a shoe part for example, in several respects, the illustrated marking head 10 is arranged to make a mark, as illustrated in 20 Fig. 8 for example, having four rows of characters, it being understood that the machine is adapted for making a mark having less or even more rows of characters if desired. This mark ordinarily comprises a customer's number 28, a legend 28, 25 and a case number 30 each of which is changed at relatively long intervals so that the ease with which they may be changed is of minor importance. The mark also comprises a match mark 32 and a size mark 34 both of which must 30 be changed frequently, at least when operating upon shoe parts, a case lot of which in ordinary shoe-making practice may include a great variety of sizes. The legend 28 and the customer's number 26 are made by type members 36, 38 35 (Fig. 3) releasably mounted in a well-known manner in plates 40 and 42, respectively, dovetailed to a supporting member 44. The plates 40 and 42, when assembled on the member 44, are locked in their operative positions by keys 46 40 the lower ends of which are adapted to enter grooves in the plates. The type members 36, 38, when thus positioned on the member 44, are spaced sufficiently to permit the movement therebetween of a row of type members 47 (Figs. 5 and 45 3) having type-carrying projections 48 and adapted to be selected to make the desired marks 30, 32 and 34. The member 44 is fixed to the lower ends of rods 49 mounted to slide vertically, for a purpose which will appear hereinafter, in 50 50 guides 50 fixed to the sides of a U-shaped bracket 51 (Fig. 2) mounted on the carrier 14.

The projections 48 extend perpendicularly from the mid-portions of bases 52 (Fig. 5) the ends of which are pivoted together by pins 53, each 55 selected type member 47 therefore being one of a chain of articulated type members having different characters thereon. Successive type members of each chain are provided with characters arranged in the sequence of their numerical or 60 alphabetical order so that in operating upon a group of work-pieces arranged in the order of their sizes, as is customary in shoe manufacture, resetting of the chains is accomplished by a step-by-step movement. In order to indicate to the 65 operator the character on the type member in operative position, each type member has its character formed on the surface of the projection 48 which faces forwardly of the machine when in operative position, as illustrated in Figs. 2 70 and 5. The chains of the type members 47 (Fig. 3) at their lower ends are looped in extended relation about a support 54 which is fixed between the lower ends of the bracket 51; and at their 75 upper ends the type chains are looped about polygonal sprockets 55 individually rotatable on

a shaft 56 the ends of which extend through vertical slots 58 in the sides of the bracket 51. The shaft 56 is supported at its ends by links 60 (Fig. 4) pivoted to a yoke 62 rotatably mounted at 64 on lugs 66 extending forwardly of the machine from the sides of the bracket 51. The type chains are normally held taut by a spring 68 fixed at its upper end to the carrier 14 and at its lower end to a rod 70 on the yoke 62, the spring 68 thus tending to elevate the yoke 62 and hence the shaft 56. As a result of yieldingly urging the type chains upwardly in the manner described above, the lowermost selected type members 47 are located in their operative positions and are aligned with each other, as will now 15 be described.

The support 54 has a seat 72 (Figs. 3 and 5) adapted to support the bases 52 of the type members 47 and of such width as completely to fill the space between the bases of the alternate type 20 members 47 at each side of the selected type member. Thus, one or both sides of the support 54 cooperate with alternate type members 47 in each chain to cause all of the selected type members to be aligned accurately with each other laterally of the marking head 10 from front to back. In order to provide uniform spacing between the selected type members 47 the type 25 chains are separated at the support 54 by thin washers 74 (Fig. 3) mounted on the support 54; 30 and similar spacing of the type chains at their upper ends is afforded by thin gears 76 (Fig. 4) one of which is fixed to each of the sprockets 55 to facilitate the resetting of a type chain, as will now be described.

Preparatory to moving a selected type member 47 into operative position, the yoke 62 is swung downwardly against the tension of the spring 68 by a lever 78 mounted on a shaft 79 pivoted between the frame members 20 and arranged to be 40 operated by a treadle-operated rod 80 which is connected to the end of a lever 81 fixed to the shaft 79. Lowering of the yoke 62 causes a corresponding lowering of the shaft 56 and hence the type chains to permit them to be moved without 45 interference with the lower corners of the support 54.

Resetting of the extreme right-hand type chain 81 (Fig. 2), which is used to mark the unit digit of the match mark 32 and which therefore is 50 frequently changed, is effected by rotating a gear 82 (Fig. 7) meshing with the gear 76 associated with the type chain 81, the gear 82 being threaded on a shaft 84 to the end of which is attached a knob 86.

A spacing member 88 surrounding the shaft 84 and extending between the gear 82 and the knob 86 is rotatably mounted in a bushing 90 fixed in the right-hand side of a yoke member 91 (Fig. 1) mounted on the bracket 51. Another bushing 60 92 coaxial with the bushing 90 and fixed in the left-hand side of the member 91 rotatably supports a tube 94 carrying a gear 96 arranged to mesh with a gear 76 associated with a type chain 98 (Fig. 2) having half-size characters on its 65 type members 47. A knob 100 (Fig. 7) is mounted on the tube 94 to facilitate resetting of the chain 98 which must be done frequently. A type chain 102 (Fig. 2) directly to the left of the chain 98 is provided with unit digit characters for making 70 the unit digit size marks and is reset by turning a knob 104 fixed to a shaft 105 within the tube 94 and carrying a gear 106 adapted to mesh with the gear 76 associated with the chain 102.

The width size, the tens digit of the match 75

mark 32 and all of the digits of the case number 30 are made by selected type members of those chains between the chains 31 and 38 and are set by means comprising gears 108 (Figs. 7 and 2) 5 rotatably mounted on a sleeve 110 into the ends of which extend pintles 112 on the adjacent ends of the shafts 84 and 105. Each of the gears 108 meshes with one of the gears 76 and is operated by one of a series of gears 114 (Fig. 3) rotatably 10 mounted on a shaft 115 supported on lugs 116 (Fig. 4) extending upwardly from the yoke member 91. Washers 118 of larger diameter than the gears 114 are arranged both to separate the gears 114 and also to prevent any interference between 15 the various gears 82. The washers 118 with the teeth of the gears 114 also form pockets into which the operator may easily insert a pointed instrument to rotate the gears 114 when it is desired to reset a type chain.

20 When the marking head 10 is in its uppermost position as illustrated in Figs. 1 and 4, the member 44 is held away from the type chains so that even though they may be lowered somewhat to permit their movement under the support 54, 25 they will not strike the member 44. To this end, bars 120 fixed by means of bolts 122 to the frame members 28 and extending forwardly of the machine are provided with adjustable stop screws 124 arranged to engage plates 126 clamped by 30 nuts 127 to the upper ends of the rods 49 in order to limit the upward movement of the member 44 in such a position as to provide adequate clearance between the member 44 and the type chains when lowered. When the marking head 10 is 35 lowered, springs 128, surrounding the rods 49 and abutting the guides 50 and collars 130 integral with the rods 49, hold the member 44 in its uppermost position until the bases 52 of the type members 47 engage the upper surface of the 40 member 44. Thereafter the member 44 is carried downwardly with the type chains, the type of the members 41, 36 and 38 then being in the same plane, and the members 47 thus supporting the member 44 against the marking pressure and 45 the force of the springs 128.

The illustrated machine is particularly suited to the use of heated type members which, when pressed against a work-piece, make a branded mark; but it is to be understood that the various 50 features of the invention are none the less applicable to machines employing other marking media such as ink, for example. Heating of the type members 47 is effected partly by an electric resistance unit 132 (Fig. 3) housed in the support 54 from which heat is transferred by radiation and conduction to the bases 52 of the type members 47 and thence to their type faces. The 55 transfer of heat to the type faces of the members 47 is furthered by conductors 134 of copper or other material having a high degree of conductivity and extending from the inner surfaces 60 of the members 47 to their type faces.

Were the unit 132 alone depended on to heat the auxiliary type members 36 and 38, the equalization 65 of their temperatures with that of the type members 47 would be difficult, especially in view of the fact that the carrier 44 is only in contact with the members 47 for a small part of each cycle. Accordingly, the type members 36 and 38 are also heated chiefly by flat coil electric 70 units 136 and 138, respectively, mounted in recesses in the member 44 and movable therewith. The members 36 and 38 are provided with heat conductors 140 similar to the conductor 134.

75 Further insurance of even heating of the se-

lected members 47, 36 and 38 is afforded by a mutual interchange of heat between them throughout the period when the bases of the members 47 are in engagement with the members 44. At such times also the proximity of the adjacent sides of the members 36, 38 to the projections 48 of the type members is conducive to an effective interchange of heat between portions of these members extending from their abutting surfaces to their type faces. Thus a 10 uniform temperature is obtained at the type faces of all the type members whereby branded characters are impressed uniformly upon a work-piece although it is engaged substantially instantaneously by the marking head.

15 As the marking head 10 might be damaged if the machine were operated before the resetting of one or more of the type chains is completed, mechanism is provided in the illustrated machine for preventing it from being treadled until the 20 yoke 62 has been moved to its uppermost position and the selected type members are alined in their operative positions. Whenever the rod 80 is lowered to permit the type chains to be reset, a hooked arm 142 (Fig. 4) fixed to the left-hand 25 end of the shaft 79 is swung under a starting lever 144 which corresponds to the lever 69 in the above-mentioned Merrick patent and is thus prevented from being operated to start the machine. The lever 144 is connected to a treadle 30 (not shown) by a treadle rod 146.

An alternative form of type chain illustrated in Fig. 6 comprises type members 148 having bases 150 the ends of which are pivotally connected by pins 152 and type-carrying projections 35 154 extending obliquely from one extremity of the bases. When in their operative positions, the projections 154 of the selected members 148 extend vertically downward and are thus positioned in lateral alinement with each other by 40 the engagement of the bases 150 of the selected members 148 and those members 148 adjacent to the selected members with converging sides 156 of a support 158 which may be substituted for the support 50.

45 Although the operation of the illustrated machine will be understood from the foregoing description it will now be briefly summarized. The type members 47 are first selected with reference to the mark which it is desired to make on a 50 work piece which is placed on the support 12. This is done by first lowering the treadle rod 86 to cause the type chains to hang loosely below the support 54 and then by manipulating the knobs 86, 100 and 104 to bring selected type 55 members 47 of the chains reset by operating these knobs into the operative position. The type chains not controlled by the knobs referred to are similarly reset by turning the gears 114 with the help of a pointed instrument. After the 60 type members 36 and 38 in the auxiliary type plates 40 and 42, respectively, have also been selected and all of the type members have been heated to a sufficiently high temperature to sear or burn the work piece which is to be marked 65 the operation of the machine may be commenced. A work piece having been placed in the proper position on the support 12, the machine is treadled, to cause the marking head 10 to move into engagement with the work and immediately 70 back again to the starting position as illustrated in Fig. 1. During the first part of the movement of the marking head 10 downwardly the auxiliary type plates 40 and 42 remain stationary, the plates 126 at this time being held in engagement 75

with the stop screws 124 by the springs 128. During this time the portion of the marking head 10 which carries the type chains moves downwardly, the type projections 48 being moved into 5 the space between the type members 38 and 39 until all the type faces of these members are substantially in the same plane and the lower surfaces of the bases 52 of the type members 47 abut the upper surfaces of the member 44. 10 Thereafter the member 44 and the members 38 and 39 partake of the movement of the marking head toward and away from the support 12 until during the retractive movement of the marking head the plates 126 again engage the stop screws 15 124. During a substantial portion of the movement of the marking head 10 before and after it is moved into the marking position, in engagement with the work piece, a mutual interchange of heat takes place between the member 44, the 20 type members 38, 39, and the type members 47 owing to the engagement of the bases 52 of the type members 47 with the member 44 and the proximity of the projections 48 of the type members 47 to the adjacent type members 38 and 39. 25 As pointed out above, the transfer of heat to the type faces of all the type members is furthered by the provision of heat conductors 134 and 140 which are made of a material having high heat conductivity, such as copper, for example, and 30 which extend substantially to the type faces on the type members.

When, after operation of the machine, it is desired to change the mark, the treadle rod 88 is depressed, thereby causing the yoke 62 to be 35 swung downwardly and the shaft 56 to be lowered so that the type chains hang loosely below the support 54 but not engaging the member 44. The setting of any chain is thereupon effected by 40 rotating its corresponding sprocket 55 to move the chain in question until the next selected type member is disposed directly beneath the support 54. In the ordinary use of the machine the mark is changed by successive digits which 45 requires merely a step-by-step movement of the chains. In such a case accordingly, a type member succeeding that in the operative position will have been heated to the desired temperature by engagement with a side of support 54 contiguous its seat 72 which supports the selected type members against marking pressure. It is apparent, 50 therefore, that so long as the type members are brought successively into the operative position there is no delay whatever in the operation of the machine so far as the heating of the type members is concerned.

When the treadle rod 88 is released the yoke 62 is swung upwardly under the influence of the springs 68, and the base 52 of the selected type member of each chain and the type members adjacent to the selected type member cooperate 60 with the seat 72 of the support 54 and its edges positively to locate the selected type member in its operative position. It will now be apparent that, owing to the positioning of each of the 65 selected type members of each type chain, all of the selected type members will be aligned accurately with respect to each other laterally of the marking head, thus insuring a mark of good appearance and obviating any likelihood of interference between the selected members 47 and the type members 38, 39.

Whenever the treadle rod 88 is depressed to permit resetting of the type chains the arm 142 is swung under the end of the starting lever 144, 70 and thereby prevents damage to the marking

head which might result from accidentally treadling the machine before the resetting of a chain or chains has been completed.

Having described the invention, what I claim as new and desire to secure by Letters Patent 5 of the United States is:

1. In a marking machine, a chain of rigid articulated type members, resetting means therefore, a support having a seat adapted to be enveloped by a plurality of type members looped about said support, means acting upon said resetting means to tension said chain whereby a selected type member is held in operative position against said seat, and means for releasing the tension on the chain whereby the chain may 15 be adjusted to move a different type member into operative position.

2. In a marking machine, a marking head comprising a plurality of type members, a support about which said members are looped and 20 having a seat adapted to support a selected member against marking pressure, said members having pivotally connected bases extending around the sides of the supporting portion of said seat when in engagement therewith, and means for 25 holding said members firmly against the seat.

3. In a marking machine, a marking head comprising a plurality of articulated type members, plural supporting means about which said type members are looped in extended relation, 30 one of said means having surfaces converging approximately in a V and arranged to cooperate with a pair of successive type members to locate one of said pair of type members in operative position, and means for urging said supporting 35 means apart thereby to hold the selected member against one of the converging surfaces.

4. In a marking machine, a plurality of type members having type faces, and means for heating said members arranged to support them 40 against marking pressure, said members having therein heat conductors adapted to transmit heat from said heating means to said type faces.

5. In a marking machine, a chain of articulated type members, a heated support about 45 which said chain is looped and adapted to support a selected type member against marking pressure, and auxiliary type members mounted in juxtaposition to said selected type member whereby by an interchange of heat between said selected 50 and auxiliary members is effected.

6. In a marking machine, a marking head comprising a plurality of type members each having a base and a projection carrying type, means for heating said members constructed and 55 arranged to support their bases against marking pressure, heat conductors disposed in said projections for transmitting heat from said heating means to the type on said projections, and auxiliary type members spaced to receive said projections, the bases and projections of said first-mentioned type members being arranged to cooperate with the adjacent sides of the auxiliary members to effect a mutual transfer of heat therebetween.

7. In a marking machine, a marking head mounted for movement between a marking and a retracted position, said head comprising a chain of articulated type members, a support about which said chain is looped, means for resetting 70 said chain to bring a selected type member into engagement with said support, an auxiliary type member disposed in juxtaposition to said selected member, and means for arresting the movement of said auxiliary type member before said head 75

is moved to its retracted position whereby it is separated from said selected member.

8. In a marking machine, a marking head mounted for movement between a marking and retracted position, said head comprising a selected type member and an auxiliary type member adjacent thereto, said selected member having a surface arranged to support said auxiliary member against marking pressure, means for yieldingly holding said auxiliary member against said selected member whereby their type faces are disposed in the same plane, and means for arresting the retractive movement of said auxiliary member whereby the said type members are separated from each other as said head is moved into its retracted position.

9. In a marking machine, a plurality of articulated rigid type members, and a relatively fixed polygonal heated support about which said members are looped, said member having heat-emitting surfaces arranged to be enveloped by successive type members one of which is the type member selected to make a mark whereby said successive type members are maintained at substantially the same temperature.

10. In a marking machine, a marking head comprising a chain of articulated type members, resetting means and a support about which said chain is normally looped under tension to hold a selected type member in operative position, means for operating said marking head, operator-controlled means for causing relative approach of said resetting means and said support whereby resetting movement of said chain is permitted, and means actuated by the operation of said operator-controlled means for preventing the operation of said marking head to mark a work-piece.

11. In a marking machine, a marking head comprising a chain of articulated links carrying type, resetting means, and a heated support fixed in said head and about which said chains are looped, said support having a plurality of intersecting heat-emitting plane surfaces coacting with a plurality of links positively to locate a selected link in operative position and adapted to heat the selected link and one adjacent thereto simultaneously.

12. In a marking machine, a chain some of the links of which are provided with marking characters, supporting means against which the chain rests when making an impression, a work support, means for causing relative movement between the chain support and the work support to mark the work, means for setting said chain, and means for tensioning said chain, said chain support and said chain cooperating to locate a character in operative position.

13. In a marking machine, a chain comprising rigid articulated links some of which are provided with type pieces, and a plurality of supports about which said chain is looped, said supports being mounted for movement relative to one another to tension the chain, one of said supports acting to support the chain as an impression is made, said support being provided with a plurality of surfaces coacting with a plurality of links in the chain positively to locate a type piece in operative position.

14. In a marking machine, a marking head provided with a plurality of type carriers, a type plate having interchangeable type members, relatively movable supports for said type carriers and said type plate constructed and arranged for separation to permit a selective movement of the

type carriers, means for heating a row of type on said carriers, and means movable with said type-plate support for heating the type members on the type plate.

15. In a marking machine, a type head having a plurality of type carriers provided with elongated type carrying projections, a plate having interchangeable type members spaced to receive a selected row of projections, a support for said type plate movable toward and away from the type carriers and adapted in one position to bring the types on the projections flush with those on the type plate, and separate heating means for said support and for said type carriers.

16. In a marking machine, a marking head comprising a support, a plurality of type carriers surrounding said support, a heater for said carriers, an auxiliary support recessed to receive a row of type members on the carriers and movable away from said type members to permit a selective movement thereof, a type plate mounted on said movable auxiliary support, removable type members carried on said type plate, and flat heating coils on said auxiliary support in conductive relation to said removable type members.

17. In a marking machine, a marking head provided with a type carrier, a type plate having interchangeable type members, relatively movable supports for said type carrier and said type plate constructed and arranged for separation to permit movement of the type carrier, means for heating selected type on the carrier, and means movable with said type-plate support for heating the type members on the type plate.

18. In a marking machine, a marking head provided with a plurality of type carriers, auxiliary type members adjacent to said type carriers, supports for said type carriers and said auxiliary type members, means for moving said supports relatively to one another to permit a selective movement of the type carriers, and means movable with the support for the auxiliary type members for heating those members.

19. In a marking machine, a marking head provided with a plurality of type carriers, a support for said type carriers, auxiliary type pieces adjacent to and in co-operative relation with said type carriers, a member for supporting said auxiliary type pieces, means for moving said member and said support relatively to one another to permit adjustment of the type, and separate means associated with the support and with the supporting member for heating the type carriers and the auxiliary type pieces respectively.

20. In a marking machine adapted for plural line marking, wherein at least one of the plural lines of marking is composed of auxiliary type pieces, a marking head comprising a type carrier support and an auxiliary type support spaced from one another and arranged to hold type elements in heat transfer relation to one another, a separate type heating means for each of said supports, the separate type heating means and the interchange of heat between the adjacent type elements insuring the even heating of all the elements, a platen, and operating means for relatively moving the marking head and platen to press the plural lines of marking simultaneously into engagement with work on the platen.

21. In a marking machine, a marking head comprising a plurality of articulated type members, said type members comprising a base and a marking character positioned at an angle to the base, resetting means, and a support about which said members are looped, said support having

converging surfaces adapted to be engaged by a pair of successive type members to locate one of said pair of type members in its exact operative position with its angularly extending marking character in work engaging position and arranged to support said type member against marking pressure.

22. In a marking machine, spaced type supports arranged for movement relatively to one another, one of said supports having a seat

adapted to support a selected type member against marking pressure, means for heating the support which supports the selected type member against marking pressure, a chain of rigid articulated type members looped about said supports, and means for moving said supports relatively to one another to produce slack in said type chain and thereby facilitate the adjustment of said type chain. 5

NEWELL V. DYER. 10
